(57) **CLAIM**

The ornamental design for a Christmas tree halo, as shown and described.

DESCRIPTION

FIG. 1 is a top perspective view of a first embodiment of a Christmas tree halo showing my new design;

FIG. 2 is a bottom perspective view thereof;

FIG. 3 is a top perspective view of a second embodiment of a Christmas tree halo in an alternate bent configuration showing my new design;

FIG. 4 is a front view thereof;

FIG. 5 is a back view thereof;

FIG. 6 is a top view thereof;

FIG. 7 is a bottom view thereof;

FIG. 8 is a left view thereof; and,

FIG. 9 is a right view thereof.

The broken lines showing of connectors in FIG. 1-9 are included for the purpose of showing environmental structure and form no part of the claimed design.
